ROAD GRADING MACHINE

Ray C. Sherman, Seattle, Wash., assignor to
Isaacson Iron Works

Application July 3, 1931, Serial No. 548,585

2 Claims. (Cl. 37—144)

This invention relates to improvements in machines for the construction and maintenance of roadways, and it has reference in particular to motorized machines of that character now generally known in trade as "Trail-builders" or "Bulldozers", and which primarily are for the purpose of earth moving, grading and excavating in road-work or roadbuilding, but which are equally applicable to other operations of a similar character.

It is the principal object of the present invention to provide an improved type of machine of the above character, employing a tractor of a crawler type as the motive and driving means, and mounting a blade for grading and earth moving forwardly of the tractor by a supporting frame which is attached pivotally to the tractor frame in such manner as to permit vertical adjustment of its forward end for the raising or lowering of the blade in accordance with any requirement of the work being done.

It is also an object of the invention to pivotally mount the grading blade on its support in such manner as to permit its being easily and readily adjusted to different angular positions relative to the direction of travel of the vehicle so as to make delivery at either side of the machine, also to provide novel means for retaining the blade rigidly at the different positions to which it may be adjusted.

Still another object of the invention is to provide novel, convenient and quick acting mechanism for raising and lowering the blade supporting frame; such mechanism including a hydraulic cylinder with piston and pump and a simple and effective means for controlling the delivery of a pressure medium by the pump to one or other sides of the piston to actuate it for raising or lowering the blade mounting frame.

Other objects of the invention reside in the novel details of construction and in the combination of parts embodied in the mechanism for raising and lowering the frame and in the valve mechanism and its controls, as will hereinafter be fully described.

In accomplishing these and other objects of the invention, I have provided the improved details of construction, the preferred forms of which are illustrated in the accompanying drawings, where-in—

Fig. 1 is a side elevation of a machine embodying mechanism made and assembled in accordance with the present invention.

Fig. 2 is a perspective view, diagrammatically illustrating the arrangement of the various levers,

links and devices for controlling the operation of the pump and the valve which controls the action of the hydraulic cylinder.

Fig. 3 is a plan view of the machine; the seat and platform being removed from the chassis for better illustration of the control and driving devices.

Fig. 4 is a sectional detail illustrating the manner of pivotally attaching the frame to the tractor and the fixing of a brace or slide by which the blade is held at its adjusted positions.

Fig. 4a is a sectional detail taken on line 4a—4a in Fig. 4.

Fig. 5 is an enlarged, sectional view of the hydraulic cylinder, the pump, and the pump driving and control devices, the valve and its controls, in this view being shown in neutral position.

Fig. 6 is a sectional view of the clutch yoke shifting connection.

Fig. 7 is a sectional view on the line 7—7 in Fig. 5 showing the arrangement of the pump gears.

Figs. 8 and 9, respectively, are diagrammatic views illustrating the position of the control devices and the control valve of the cylinder, first, for lowering, and second, for raising the grader blade.

Referring more in detail to the drawings—

In a preferred form of construction, the grading or road working machine embodied by this invention, utilizes a tractor of the crawler or self-laying track type. Such a tractor would include an engine, or motor, of a suitable character having sufficient power to effectively and without difficulty carry on the work required of the machine. The function of the engine would be in this instance not only to propel the vehicle, but also to actuate the mechanism provided for raising and lowering the grading blade, as occasion arises.

As shown best in Fig. 1, the tractor in its entirety is designated by reference character 1, and it includes the usual frame or chassis 2, which mounts the engine, indicated at 3. At opposite sides of the chassis are track mounting frames 4—4 and at the forward ends of these frames are track mounting wheels 5. Mounted on the main frame or chassis 2, rearward of the track frames are the track driving sprockets 6. The traction belts or tracks 7—7 operate about the wheels 5 and 6 and, as here illustrated, are made up of pivotally joined shoes. The longitudinal runs of these tracks are mounted for travel on idler wheels 8 carried by the track frames.

In this construction the rear sprockets 6 are 55

driven by geared connections with the engine shaft 10 through a suitable transmission mechanism, as at 11, differential gearing of a suitable type of construction, including the differential shafts 9 on which the sprockets 6 are mounted.

The track frames 4-4, near their rearward ends, are supported or mounted upon the outer ends of a dead axle 15 which supports the rearward end portion of the vehicle frame, and the opposite end portions of this dead axle project beyond the frames sufficiently that they serve as supports on which the blade mounting frame, presently described, is pivotally mounted.

As best shown in Figs. 1 and 3, a grading blade 18 is pivotally mounted at a point midway of its ends by a pivot bolt 19, upon the forward end of a supporting frame. This frame is in the form of a yoke and it comprises opposite side beams 20-20 and a forwardly pointed base, or connecting beam 21 joining the side beams rigidly at their forward ends. This yoke encloses the forward end and opposite sides of the tractor and the rearward ends of the side beams are pivotally mounted upon the opposite ends of the axle 15 so that the forward end of the blade mounting frame may swing upwardly or downwardly for raising or lowering the blade to best suit the work being done.

As shown in Fig. 4, the beams 20-20 have bearing brackets 23 bolted to their inner sides at the rear ends, and these brackets contain bearings 24 which are rotatable on the ends of axle 15.

The blade 18 is straight from end to end and is of sufficient length that its ends will be beyond the longitudinal lines of the sides of the machine. At the back side of the blade, centrally thereof, is a flange 25 co-operating with a bearing block or plate 26 at the forward end of the blade mounting frame to receive the pivot bolt 19. Likewise, at the opposite ends of the blade are flanges 27-27 to which the forward ends of brace beams 28-28 are pivotally attached by pivot bolts 29. These beams are in the form of inwardly facing channels, and they slidably overlie the beams 20-20, and have apertures 30 adapted to register with apertures 31 in beams 20 to receive locking pins 32, as a means of rigidly holding the beams and blade at any set position. By reference to Fig. 3, it will be observed that the blade may be adjusted to oppositely directed angular positions, to deliver to either side of the machine, and it is apparent that it would be adjusted and held at any desired position between those limits, simply by removing the pins 32 and swinging the blade to the position desired; the adjustment then being retained by inserting the pins through the aligned apertures.

Fixed to the track frames 4, near their forward ends, are brackets 35 that are formed with vertical guide plates 34a spaced somewhat outside of the track belts and with which the forward end portions of the beams 20 engage to prevent lateral play of the blade mounting frame.

Rigidly fixed to the rear end of each of the side beams 20-20 of the blade frame is an upwardly directed lever 35. These are connected, by braces or tie beams 36, with the forward ends of the beams 20 through web plates 37. Mounted transversely of the machine frame at the rear end thereof and above the level of the tracks, is a rock shaft 40 rotatably mounted in bearings 41 fixed on a cross beam 42 rigidly fixed to the vehicle frame. Fixed to the opposite ends

of shaft 40 are downwardly extended lever arms 43 pivotally connected at their ends by links 44 to the upper ends of the levers 35. Fixed to the central portion of shaft 40 is a rearwardly extended rocker lever 46. A hydraulic cylinder 47 is pivotally supported in the vehicle frame below lever 46 and this contains a reciprocable piston 48 having a piston rod 49 connected by a pivot pin 50 at its upper end to the end of lever 46. The connections just described are such that reciprocal action of the piston will effect a rocking action of shaft 40 and this, in turn, operates to raise or lower the blade according to the direction and extent of movement of the piston.

Movement of the piston is effected by the pumping of a fluid pressure medium within the cylinder and this is under control of a pump 52 as illustrated in Figs. 5 and 7. The pump housing is attached to or formed as a part of the hydraulic cylinder and it comprises the intermeshing gears 55 and 56 rotatably fitted in the housing. A port 57 opens from the upper end of the cylinder into the pocket 58 above the meshing teeth of the gears, and a channel 59 leads from the pocket 60 below the meshing teeth into the lower end of the cylinder. A back check ball valve 61 is contained in this channel, as seen in Fig. 5. The pump gear 56 revolves freely on an axis 62, while gear 55 is fixed on a driving shaft 65 which is connected through flexible joints 66 with a counter shaft 67 supported in the transmission housing 68 in alignment above the engine shaft. A gear 70 keyed on the end of the engine shaft drives a gear 71 revolvably mounted on shaft 67 and formed with a clutch head 72 containing clutch disks 73. A clutch collar 74 is slideable on the shaft 67 and carries clutch disks 75 intermeshing with disks 73 in such manner that when the disks are tightened together a driving connection is effected between the engine shaft 40 and shaft 67 to drive the pump so as to effect a forcible delivery of pressure medium from the upper end of the cylinder into the lower end to raise the piston.

The lowering of the piston is under control of a rotary valve 80 in a housing 81 fixed to the outer side of the hydraulic cylinder. This housing has channels 82 and 83 communicating respectively with upper and lower ends of the cylinder, and the valve plug has a by-pass channel 84 adapted, when the plug is rotated to a certain position, to provide a connection between channels 82 and 83 for by-passing the liquid medium from the lower into the upper end of the cylinder to permit lowering of the piston.

The valve plug has a lever 85 for rotating it, and this is connected by a link 86 with a lever arm 87 on a rotatably mounted cross shaft 89. The shaft 89 is actuated by manipulation of a hand lever 90 pivotally mounted at its lower end by pivot 91, and connected by link 92 with a lever arm 93 fixed on the shaft. A spring actuated latch tooth 94 is slidably mounted on the hand lever and this engages at its lower end in a notch 95 of a fixed segment 96 to retain the lever in what is known as neutral position. A grip lever 97 is mounted pivotally on the upper end of the lever 90 and connected with the latch tooth by a rod 98. Depression of the grip releases the tooth from its holding contact with the segment.

The driving clutch for the pump is set by movement of the hand lever 90 from neutral position rearwardly, and this is effected by reason of a connection shown best in Fig. 6 wherein 100 designates a short lever arm fixed to cross shaft 75

89 and extended downwardly. A link or rod 101 is connected at one end to the arm, as at 102, and at its other end is slideable through a hole 103 in the base end of a yoke like link 104. A stop 105 is fixed on rod 101 to limit its forward sliding movement in the yoke and a coiled spring 106 bears against the yoke end and against a nut 107 on the end of the rod to yieldingly pull the yoke rearwardly with the rod. At its forward end the link 104 connects with a clutch shifting yoke 110. This is pivotally suspended by a pivot 111 from a bracket 112 fixed to the housing, or to any other convenient support. The yoke 111 has a pin and slot connection as at 113 with the clutch and the parts are so arranged that movement of the hand lever 90 rearwardly from neutral position rocks the cross shaft 89 and this, in turn, causes a forward swinging of the lever arm 100 and this causes the clutch to be set to thus complete the driving connection from the engine shaft 10 to the pump.

Assuming the parts to be so constructed and assembled, the operation would be as follows:

First assuming that the grader blade is fully lowered and that the piston 48 is at its lower limit in the hydraulic cylinder 47; when it is desired to elevate the grader blade the operator pulls the hand lever 90 rearwardly from neutral position, as to the position of Fig. 9, thus rotating the cross shaft 89 and, through the linkage shown, rotating the valve plug to a position closing the by-pass channels. By the same movement, the clutch shifting rod 101 moves forwardly, its stop 105 engages yoke link 104 to shift yoke 110 and sets the clutch to start the pump. The pump then delivers fluid from the upper into the lower end of the cylinder and elevates the piston and this effects the raising of the grader blade. To stop the raising movement it is only necessary to pull the hand lever 90 back to neutral position. This movement releases the clutch, but the by-pass still remains closed, therefore the trapped liquid in the cylinder holds the piston against downward movement.

When it is desired to lower the blade, the hand lever 90 is pushed forwardly, as in Fig. 8. This action rotates shaft 89 to swing the valve lever 85 rearwardly to open the by-pass channel 84 through the valve and thus permit liquid to flow from the lower into the upper end of the cylinder

and the piston to be lowered accordingly. When the hand lever is pushed forwardly, it places the spring 107 under compression and therefore, when it is desired to stop the lowering movement, it is only necessary to release the lever and it is brought automatically back to neutral position by expansion of the spring. It is not required to drive the pump for a lowering operation, therefore the clutch is not set by this movement.

The present mechanism is relatively simple. It is effective and efficient, readily responsive and easily controlled. There is a safety factor in that only for elevating the blade is power applied, and should the operator fail to release the drive after the parts have been fully elevated, the liquid will simply be cut off from the intake port by the piston passing over it.

Having thus described my invention, what I claim as new therein and desire to secure by Letters Patent is:

1. In combination, a tractor including a frame structure and a driving motor, a dead axle mounted in the frame structure with its ends extended at opposite sides thereof, track frames pivotally mounted on said extended ends and tracks operable about said frames, a blade mounting frame comprising opposite side beams pivotally mounted at their rearward ends on the extended ends of the dead axle, a ground working blade mounted by the frame forwardly of the tractor, and means for sustaining the vertically movable end of the blade mounting frame at different operative positions.

2. In combination, a tractor including a main frame, a dead axle mounted in the frame and having ends extended at opposite sides thereof, track frames mounted pivotally at their rearward ends on said extended ends, traction belts operable on said frames, a blade mounting frame 40 comprising opposite side portions pivotally mounted on the ends of the dead axle outside the track frames and extended forwardly of the traction, and a beam connecting the forward ends of the said side beams across their front ends, a blade 45 pivotally mounted on the cross beam and adjustable to different angular positions, and means on the main frame for raising and lowering the forward end of the blade mounting frame.

RAY C. SHERMAN. 50
